UNITED STATES PATENT OFFICE.

JOHN M. G. DARMS, OF BUFFALO, NEW YORK.

TOILET-PAD.

992,173.

Specification of Letters Patent. Patented May 16, 1911.

Application filed November 12, 1909. Serial No. 527,697.

To all whom it may concern:

Be it known that I, JOHN M. G. DARMS, a citizen of the United States, residing at Buffalo, in the county of Erie and State of New York, have invented a new and useful Toilet-Pad, of which the following is a specification.

This invention relates to antiseptic covers for water closet seats and its principal object is to provide an inexpensive device of this type which can be folded into a compact bundle and thus carried conveniently in a small antiseptic case, it thus being rendered especially useful to travelers, students, and others who are compelled ordinarily to use public toilets.

A still further object is to provide a device of this character having simple means whereby it can be readily placed in position upon the seat.

With these and other objects in view the invention consists of certain novel details of construction and combinations of parts hereinafter more fully described and pointed out in the claim.

In the accompanying drawings the preferred form of the invention has been shown.

In said drawings, Figure 1 is a perspective view showing the device in position upon a seat. Fig. 2 is a view showing the pad rolled into a compact bundle ready to be placed in a case or pocket.

Referring to the figures by characters of reference 1 designates the cover which is preferably made of a suitable waterproof fabric having smooth surfaces designed to prevent the lodgment of germs and parasites, the said cover being so shaped as to conform to the outline of a water closet seat so that, when it is in position, it will prevent any portion of the seat from coming into contact with the body.

In order to quickly and securely attach

the device to a seat, a series of hooks 2 may be utilized, these hooks being located at desired points adjacent the outer edge of the cover and being preferably attached thereto by means of rivets 3 so that when it is desired to fold the device the hooks can be swung into position between the edges of the cover. A loop 4 may be extended from the cover, the same constituting means whereby the device can be hung from a nail or the like.

When it is desired to use the device the hooks are placed in engagement with the edge portion of the seat and the cover is thus held upon all portions of the seat and serves to keep the body out of contact with the seat. When the device is not in use it can be folded into a very compact package which may be placed within a small antiseptic case capable of being carried within the pocket.

It is of course to be understood that various changes may be made in the construction and arrangement of the parts without departing from the spirit or sacrificing any of the advantages of the invention.

What is claimed is:

As an article of manufacture, a seat cover, consisting of a single piece of material adapted to be flexed in any direction to form a compact bundle, there being an opening within said cover, and means movably connected to the marginal portion of the cover, for detachably engaging the edge portion of a seat to hold the cover stretched upon the seat.

In testimony that I claim the foregoing as my own, I have hereto affixed my signature in the presence of two witnesses.

JOHN M. G. DARMS.
